UNITED STATES PATENT OFFICE.

HERBERT IRVING EMMONS, OF LAWRENCE, MASSACHUSETTS.

SHUTTLE-CHECK MEANS FOR LOOMS.

Application filed October 31, 1922. Serial No. 598,236.

To all whom it may concern:

Be it known that I, HERBERT I. EMMONS, a citizen of the United States, residing at the city of Lawrence, county of Essex, 5 State of Massachusetts, have invented new and useful Improvements in Shuttle-Check Means for Looms, of which the following is a specification.

This invention relates to improvement in shuttle check means for looms, more especially upon the subject-matter of Letters Patent granted to Francis A. Mills, May 15, 1906, Number 820,663.

The leading characteristic of the improvements consists principally in the employment of a cushioning binder for the shuttle, whereby the requisite shuttle-check action may be, and is obtained for the shuttle. The solution for this problem is found in providing means adapted to so function as to effectively counteract the rebounding action of the shuttle and lessen the impact which would otherwise result from the throw of the shuttle and its contact with the binder. These objections and deficiencies are in evidence, or prevalent, in this type of devices universally, as has been borne out by practical demonstration. As indicated, my invention consists in the provision of a cushioning binder, as for instance, such a binder formed of sponge or highly porous rubber which, it is found, while possessing the requisite resistance as a binder or buffer, also possesses the pliability needed to serve as a cushion whereby to function in the twofold capacity pointed out, and which also will not become irritated or hardened by wear, as by the frictional or precipitate contact of the shuttle therewith, as when the binder is of "hard" rubber, as heretofore has been experienced in this art. It is further observed that by the use of the hard rubber binders or buffers, such is not the requisite pliability or yielding character to meet the qualifications demanded, which, however, have been fulfilled by the use of my invention. Also, it is observed that the hard rubber binder, by reason of the absence of the softness or cushioning effect or action of my buffer or binder, is not adapted to provide the shuttle with the requisite shuttle-check as it acts or functions as a plain hard leather surfaced binder as the shuttle contacts therewith. With the use of the binder or buffer and the front of the iron-

shuttle-box or case covered with the sponge-rubber, the shuttles will be checked and the loom may be run without check-strap, which is a great saving to a mill- 60 equipment, as these check-straps are quite expensive and wear out often. By the use of the soft or sponge-rubber the shuttles are subjected to lessened frictional contact, also the latter are held in their boxes be- 65 sides, saving a great deal of loom trouble, and the looms may be run faster, while the life of the loom parts may be greatly lengthened.

The invention consists, therefore, of cer- 70 tain instrumentalities and features of construction, including their arrangement substantially as hereinafter more fully disclosed and pointed out by the claim.

The following description, read in con- 75 nection with the accompanying drawings, will enable any one skilled in shuttle check and locking mechanism for looms to understand my invention and to practice it in the form in which I prefer to employ it; 80 but it will be understood that my invention is not limited to the precise form and details of construction herein illustrated and described, as various modifications and changes may be made without departing 85 from the scope or spirit of my invention and claim.

Referring to the drawing,

Figure 1 shows in top view the left shuttle-box of the lay, having the binder lo- 90 cated at the back thereof and the shuttle in position, having just come in contact with the cushioning binder.

Fig. 2 shows a like view, the shuttle hav- 95 ing fully entered the shuttle-box and in contact with the picker and the picker-stick to actuate an impact-strap to force the binder against the shuttle to check and lock it.

Fig. 3 shows a side view of the same. 100

Fig. 4 is a longitudinal section of the binder, taken on the line 4-4 of Fig. 5, showing my novel cushioning shuttle- 105 binder.

Fig. 5 is a cross-section of the same on the line 5-5 of Fig. 4.

Fig. 6 shows the front side of the left end of the box and means for adjusting the impact-strap to cause the shuttle to be stopped and locked at the predetermined position in the shuttle-box. 110

Fig. 7 shows the protection-finger ar-

ranged to operate the binder between the latter and the impact-strap.

Fig. 8 shows the same in top view.

Among other features which may be considered as incidental to the present disclosure of my invention, I arrange the impact-strap so as to yieldably force a shuttle-binder against the shuttle. To cause this operation, I provide a novel arrangement and connection of the impact-strap with the shuttle-binder to cause the latter to be yieldingly pressed upon the shuttle by the impact of the shuttle upon the picker.

15 The lay 1, the shuttle-box 2 therein, the shuttle 3, and picking mechanism therefor, may be of the usual form and construction. As above indicated, the leading or main feature of my present disclosure or invention consists in the employment of a binder, buffer, or cushion of a soft and light character, preferably and essentially what is known as sponge-rubber, as differentiated from what is styled as hard rubber, as 20 means for checking and locking the shuttle of a predetermined position within the shuttle-box, the detailed description of which operation follows.

An impact-strap 4 is arranged at the back 30 of the binder and has one end 5 connected to the lay or shuttle-box, passing across a movable part 6 of a binder 7 around the picker-stick 9 and fastened to adjustable means which is connected to the box or lay, 35 so that the impact of the shuttle upon the picker or pickerstick will cause impact upon the strap to cause it to force the binder against the shuttle.

While I have shown the impact-strap as 40 crossing the path of the picker-stick above the lay, obviously that part of the strap which receives the impact of the picker or picker-stick caused by the shuttle may be dropped beneath the lay around the picker-stick and adjustably connected to the lay.

The binder is pivoted to the lay and may 50 form one side of the shuttle-box. Referring to the impact-strap, the means for adjusting it to provide for the stretch of the strap and wear of the picker by the impact of the shuttle, so as to stop the shuttle at a predetermined position in the shuttle-box, are seen in Figs. 1, 2, and 6, and consists of a 55 revolute stud or post 14, secured by a clamp-nut to a bracket 15, which is bolted to the lay, and to said post the strap is fastened and wound around it, so that by loosening said nut on the stud or post the latter may be turned to wind up or let out 60 the strap for its adjustment. I also provide means for laterally adjusting the fulcrumed end of the binder, and for this purpose the binder-fulcrum 16 is an eccentric, and by loosening a nut 17, and turning the eccentric,

65 in or out from the opposite side of the shuttle-box. This adjustment of the shuttle-binder at its fulcrumed end is to give more or less lifting action to the protection mechanism and pressure upon the shuttle.

70 Looking at Fig. 1, it will be seen that the shuttle has struck the swell of the binder with a cushion effect, this giving easy entrance to the box. The shuttle having entered fully in the box, as seen in Fig. 2, it 75 will be noticed that the binder has been compressed by the impact of the shuttle upon the picker, and thereby cause a pulling action of the impact-strap which has forced said binder against the shuttle with 80 a locking function upon the shuttle to lock it at the desired position in the shuttle-box.

The protection device is of the usual form, having the protection-finger 18, its shaft 19, and spring 20 for forcing the finger against the binder, and looking at Figs. 1, 2, and 3, it will be seen that the protection-finger is in engagement with, and pressing upon the impact shuttle-locking strap, said strap or band being shown located between the protection-finger and the movable end of the binder, so that when the shuttle strikes the binder, forcing its free end out, will cause said strap to be frictionally drawn under spring-pressure between said binder and the protection-finger, thereby aiding in checking the shuttle while traveling in the box. The protection-finger, however, may be located between the shuttle-locking impact strap and the binder, as seen in Figs. 7 and 8, which will cause said strap to force the protection-finger against the shuttle-binder and said binder against the shuttle to lock it.

105 Looking at Fig. 4 it will be understood that the impact-facing of the binder will have in its contact with the shuttle, a yielding function due to the elasticity of the rubber, the combined effect of both these yielding elements being to cause the binder to conform to the shape of the shuttle while traveling and at the limit of its travel in the shuttle-box.

I claim:

115 In a loom, including its shuttle, the combination therewith of a cushioning binder comprising essentially a relatively soft and pliable material consisting of sponge-rubber, a lay, a shuttle-box, picking mechanism, an impact strap connected at one end of said shuttle-box or lay, passing over a movable part of the binder, crossing the path of the picker or picker-stick, and connected to said shuttle-box or lay, at its other end.

120 In testimony whereof I hereby affix my signature.

HERBERT IRVING EMMONS.
